UNITED STATES PATENT OFFICE

HUBERT R. HUMPHREY AND GEORGE A. HUMPHREY, OF KALAMAZOO, MICHIGAN, AS
SIGNORS TO GENERAL GAS LIGHT COMPANY, OF KALAMAZOO, MICHIGAN

HEATING APPARATUS

Application filed January 23, 1929. Serial No. 334,546.

Our present improvements are especially adapted to and we have described the same herein as embodied in the type of heater illustrated in our application for Letters 5 Patent filed November 3, 1928, Serial No. 314,017.

The main objects of this invention are:

First, to provide a heating apparatus having a radiating unit consisting of a plurality of radiating flues in which the parts are easily assembled and are not distorted or disarranged by expansion and contraction resulting from heating and cooling.

Second, to provide a heating apparatus 15 having a closed combustion chamber in which the burner parts are housed within the combustion chamber and at the same time all parts are fully accessible for replacement, cleaning or the like.

20 Objects relating to details and economies of our invention will appear from the description to follow. The invention is defined and pointed out in the claims.

A structure which is a preferred embodiment of our invention is illustrated in the accompanying drawings, in which:

Fig. 1 is a front perspective view of our improved heating apparatus with the burner housing shown in open position by full lines 30 and in closed position by dotted lines, the gas supply pipe and supports being broken away.

Fig. 2 is a fragmentary front elevation view.

Fig. 3 is a fragmentary view mainly in 35 vertical section on line 3—3 of Fig. 2.

Fig. 4 is a fragmentary view partially in vertical section on line 4—4 of Figs. 5 and 6.

Fig. 5 is a fragmentary view partially in vertical section on line 5—5 of Fig. 4.

40 Fig. 6 is a fragmentary view partially in vertical section on line 6—6 of Fig. 2.

Fig. 7 is a perspective view of one of the flue clamping strips.

Fig. 8 is a fragmentary section on line 8—8 45 of Fig. 3.

In the embodiment of our invention illustrated, we provide a base member 1 open at the bottom and provided with a plurality of flue openings 2 in the top wall thereof.

50 The top member 3 is provided with flue

openings 4 aligned with the openings 2. These flue openings are arranged in aligned rows.

The parts 1 and 3 are connected in spaced relation by means of the tie rods 5, the ends of the tie rods being arranged in opposing seats in the parts and secured in the seats by the screws 6.

Radiating flues 7 are disposed through the openings 4 in the top member with their lower ends projecting in the openings 2 in the base member. The upper ends of the flues are inwardly tapered at 8 providing restricted discharge openings 9.

The flues are also provided with annular bead-like shoulders 10 resting upon the top member and clamped thereto by means of the clamping strips 11 preferably of spring material, the strips being arranged between the rows of flues to engage the shoulders thereof and clamped thereon by means of the screws 12. The flues are thus effectively retained in position, being secured to the top member while their lower ends are free to move or adjust themselves in the openings in the base member so that the flues are not distorted by the expansion and contraction thereof resulting from heating and cooling and the parts are not put under undue stress by such expansion and contraction.

The header member 13 is mounted on the top member and coacts therewith in providing a header for the flues, the discharge flue 14 being connected centrally to the header.

The apparatus is supported by the hangers 15 engaged with lugs 16 on the base and passed through ears 17 on the top member.

A louver housing 18 is mounted at the front, the side members 19 of this housing being disposed in overlapping relation to the tie rods 5 and secured thereto by the screws 20. The louvers 21 are independently adjustable in this housing.

We provide a box-like burner housing 22 having forwardly projecting pivot ears 23 on its front wall secured to the vertically adjustable hinge members 24 by means of the pivots 25 so that the burner housing may be swung downwardly to expose the parts mounted therein or secured in operative posi-

tion to complement the base member providing a closed combustion chamber 26. With the parts thus arranged when the burner housing is open, the burner parts are all accessible for renewal, cleaning or adjustment, and also the flues are exposed for cleaning which is an important feature.

The burner housing is retained in its closed position by means of the bolts 27 engaging lugs 28 and also the gas delivery pipe 29 which is secured by the coupling 30 to a nipple 31 depending from the supply valve 32. The delivery pipe 29 delivers to a gas header 33 mounted on the front wall of the burner housing and provided with a plurality of inwardly directed gas nozzles 34.

On the rear wall of the housing we mount a plurality of burner members each consisting of a header 35, a mixing tube 36 which projects across the burner housing into coacting relation with one of the nozzles, and a plurality of burners 37. The rear wall of the housing is recessed at 38 or has openings therein to receive the mixing tubes and burners, the heads constituting closures for these openings.

The rear wall 39 of the housing is disposed in a plane at the rear of the rear wall of the base member and coacts with an air passage 40 providing an air inlet passage 41 delivering at the bottom of the combustion chamber. This passage member 40 constitutes a part of the blower hood 42 arranged at the rear of the structure in operative relation to the blower consisting of the motor 43 and fan 44 on the front end of the motor shaft 45. The rear end of the shaft 45 carries a governor device 46 operatively associated with the valve 32 so that the gas valve is opened or permitted to open only when the motor is in operation. This mechanism is made the subject matter of one of our co-pending applications.

The lower edge of the passage member 40 is notched at 47 to receive the burners. With the parts thus arranged the burner header members constitute closures for the joint between the passage member and the rear wall of the burner housing.

With this arrangement, we provide a closed combustion chamber, the primary and secondary air inlets being within this chamber. Air is delivered by the blower to this combustion chamber and also across the radiating flues, a forced circulation resulting through the flues which have restricted discharges, the apparatus being highly efficient. Claims, however, are made to these features broadly in our said application for Letters Patent, Serial No. 314,017.

We have not attempted to illustrate or describe various adaptations of our present improvements which we contemplate as we believe this disclosure will enable those skilled

in the art to embody or adapt our improvements as may be desired.

Having thus described our invention, what we claim as new and desire to secure by Letters Patent, is:

1. In a heating apparatus, the combination of a chambered base member open at the bottom and provided with a plurality of flue openings in the top wall thereof arranged in rows, a top member having a plurality of flue openings therein aligned with said openings in said base member, tie rods connecting said members in spaced relation, radiating flues having annular bead-like shoulders adjacent their upper ends arranged through said openings in said top member with their shoulders in engagement therewith and their lower ends projecting into said openings in said base member, flue clamping strips arranged between said adjacent rows of flues in engagement with the said shoulders thereof, a flue header member mounted on said top member to coact therewith to provide a flue header, a burner housing member mounted on said base member and coacting therewith to provide a combustion chamber, and a burner mounted in said burner housing member. 70

2. In a heating apparatus, the combination of a chambered base member open at the bottom and provided with a plurality of flue openings in the top wall, a top member having a plurality of flue openings therein aligned with said openings in said base member, tie rods connecting said members in spaced relation, radiating flues arranged through said openings in said top member and secured thereto in engagement therewith and their lower ends projecting into said openings in said base member, a flue header member mounted on said top member to coact therewith to provide a flue header, a burner housing member mounted on said base member and coacting therewith to provide a combustion chamber, said burner housing member being pivotally mounted on said base member, and a burner mounted on said burner housing member. 80

3. In a heating apparatus, the combination of a chambered base member provided with a plurality of flue openings in the top wall, a top member having a plurality of flue openings therein aligned with said openings in said base member, tie rods connecting said members in spaced relation, radiating flues arranged through said openings in said top member and secured thereto in engagement therewith and their lower ends projecting into said openings in said base member, a flue header member mounted on said top member to coact therewith to provide a flue header, a burner housing member mounted on said base member and coacting therewith to provide a combustion chamber, and a burner mounted on said burner housing member. 90

4. In a heating apparatus, the combination 100

of a base member provided with a plurality of flue openings arranged in rows, a top member having a plurality of flue openings therein aligned with said openings in said base member, means connecting said members in spaced relation, radiating flues tapered at their upper ends providing restricted discharge openings and having annular bead-like shoulders adjacent their upper ends arranged through said openings in said top member with their shoulders in engagement therewith and their lower ends projecting into said openings in said base member, and flue clamping strips arranged between said adjacent rows of flues in engagement with the said shoulders thereof.

5. In a heating apparatus, the combination of a base member provided with a plurality of flue openings arranged in rows, a top member having a plurality of flue openings therein aligned with said openings in said base member, means connecting said members in spaced relation, radiating flues having annular bead-like shoulders adjacent their upper ends arranged through said openings in said top member with their shoulders in engagement therewith and their lower ends projecting into said openings in said base member, and flue clamping strips arranged between said adjacent rows of flues in engagement with the said shoulders thereof.

6. In a heating apparatus, the combination of a combustion chamber member having a plurality of flue openings therein, a header member having a plurality of flue openings therein aligned with said openings in said combustion chamber members, tie rods connecting said header and combustion chamber members, radiating flues having shoulders at their upper ends arranged through said openings in said header member with their shoulders in engagement therewith with their opposite ends in said openings of said combustion chamber member, and clamping members on said header member engaging said shoulders on said flues.

7. In a heating apparatus, the combination with a base member open at the bottom, of a burner housing coacting with said base member to provide a closed combustion chamber, the rear wall of said housing being disposed in spaced relation to the rear wall of the base member, an air passage member coacting with the rear wall of said housing to provide an air passage to said combustion chamber, a gas header provided with a plurality of inwardly facing gas delivery nozzles mounted on the front wall of said burner housing, a plurality of burner units mounted on the rear wall of said housing and each comprising a chambered head member, a mixing tube delivering to said head member and extending across the burner housing into coacting relation with one of said gas nozzles, a plu-

rality of burners on each head member, the rear wall of said housing having openings therein to receive said mixing tubes and burners, the burner heads constituting closures for said openings, the lower edge of the passage member being notched to receive said burners, a gas supply valve, a vertically adjustable pivotal support secured to the front of said housing, and a gas delivery pipe for said header mounted on said housing to project from the rear wall thereof and detachably connected to said gas valve.

8. In a heating apparatus, the combination with a base member open at the bottom, of a burner housing coacting with said base member to provide a closed combustion chamber, a gas header provided with a plurality of inwardly facing gas delivery nozzles mounted on the front wall of said burner housing, a plurality of burner units mounted on the rear wall of said housing and each comprising a chambered head member, a mixing tube delivering to said head member and extending across the burner housing into coacting relation with one of said gas nozzles, a plurality of burners on each head member, a gas supply valve, a pivotal support for the front of said housing, and a gas delivery pipe for said header mounted on said housing to project from the rear wall thereof and detachably connected to said gas valve.

9. In a heating apparatus, the combination with a base member open at the bottom, of a burner housing coacting with said base member to provide a closed combustion chamber, the rear wall of said housing being disposed in spaced relation to the rear wall of the base member, an air passage member coacting with the rear wall of said housing member to provide an air passage to said combustion chamber, a gas header provided with a plurality of inwardly facing gas delivery nozzles mounted on the front wall of said burner housing member, a plurality of burner units mounted on the rear wall of said housing member and each comprising a chambered head member, a mixing tube delivering to said head member and extending across the burner housing into coacting relation with one of said gas nozzles, said mixing tubes having air inlets within said housing a plurality of burners on said head member, the rear wall of said housing having openings therein to receive said mixing tubes and burners, the burner heads constituting closures for said openings, the lower edge of the passage member being notched to receive said burners, and means for supporting said burner housing so that it may be opened.

10. In a heating apparatus, the combination with a base member open at the bottom, of a burner housing coacting with said base member to provide a closed combustion chamber, an air passage member coacting with the rear wall of said housing member

to provide an air passage to said combustion chamber, a gas header provided with a plurality of inwardly facing gas delivery nozzles mounted on the front wall of said burner housing member, a plurality of burner units mounted on the rear wall of said housing member and each comprising a chambered head member, a mixing tube delivering to said head member and extending across the burner housing into coacting relation with one of said gas nozzles, said mixing tubes having air inlets within said housing, a plurality of burners on each head member, and means for supporting said burner housing so that it may be opened.

11. In a heating apparatus, the combination with a base member open at the bottom, of a burner housing coacting with said base member to provide a combustion chamber, a gas header provided with a plurality of inwardly facing gas delivery nozzles mounted on the front wall of said burner housing member, a plurality of burner units mounted on the rear wall of said housing, a mixing tube delivering to said header member and extending across the burner housing into coacting relation with one of said gas nozzles, a gas supply valve, a vertically adjustable pivotal support secured to the front end of said housing, and a gas delivery pipe for said header mounted on said housing to project from the rear wall thereof and detachably connected to said gas valve.

12. In a heating apparatus, the combination with a base member open at the bottom, of a burner housing coacting with said base member to provide a combustion chamber, a gas header provided with a plurality of inwardly facing gas delivery nozzles mounted on the front wall of said burner housing member, a plurality of burner units mounted on the rear wall of said housing, a mixing tube delivering to said header member and extending across the burner housing into coacting relation with one of said gas nozzles, and a pivotal support for said housing.

13. In a heating apparatus, the combination with a base member open at the bottom, of a burner housing coacting with said base member to provide a combustion chamber, a burner mounted on said housing, a vertically adjustable pivotal support connected to said housing at one side thereof, a gas delivery pipe for said burner mounted on said housing, and means for detachably connecting said delivery pipe to a supply pipe.

14. In a heating apparatus, the combination with a base member open at the bottom, of a burner housing coacting with said base member to provide a combustion chamber, a burner mounted on said housing, and a vertically adjustable pivotal support for said housing.

15. In a heating apparatus, the combina-

tion with a base member open at the bottom, of a burner housing coacting with said base member to provide a combustion chamber, a burner mounted on said housing, a pivotal support for said housing, and a gas delivery pipe for said burner constituting a support for said housing.

In witness whereof we have hereunto set our hands.

HUBERT R. HUMPHREY.
GEORGE A. HUMPHREY.
